Primary Examiner — R. Johnson(74) *Attorney, Agent, or Firm* — Robert L. Wolter; Beusse, Wolter, Sanks & Maire PLLC**CLAIM**

The ornamental design for a gravity latch, as shown and described.

DESCRIPTION

FIG. 1 is a rear left perspective view of a gravity latch in accordance with the present invention;

FIG. 2 is a rear right perspective view thereof;

FIG. 3 is a front perspective view thereof;

FIG. 4 is a left side view thereof;

FIG. 5 is a right side view thereof;

FIG. 6 is a top plan view thereof;

FIG. 7 is a bottom plan view thereof;

FIG. 8 is a rear elevational view thereof; and,

FIG. 9 is a front elevational view thereof.

The broken lines shown represent unclaimed subject matter and form no part of the claimed design.
